UNITED STATES PATENT OFFICE.

JOHN REBEL, OF CLEVELAND, OHIO.

INFLATABLE BATHING-GARMENT.

1.303.389.

Specification of Letters Patent. Patented May 13, 1919.

Application filed July 29, 1918. Serial No. 247,136.

To all whom it may concern:

Be it known that I, JOHN REBEL, a citizen of the United States, residing at Cleveland, in the county of Cuyahoga and State 5 of Ohio, have invented certain new and useful Improvements in Inflatable Bathing Garments, of which the following is a specification.

My invention consists of an inflatable bathing garment made of separate plies of woven fabric and sewed together to provide divisional air compartments in localized areas therein, and as constructed the garment is simple and may be readily inflated by the wearer and secured upon and used by a person with comfort and convenience.

In the accompanying drawing, Figure 1 is a front view of the garment deflated, and Fig. 2 is a side view thereof inflated. Fig. 3 is a cross section of the garment inflated, and Fig. 4 is a sectional view of one side portion of the garment, partially deflated.

portion of the garment, particularly
20 The garment comprises a body portion 2
25 having a pair of shoulder straps 3, one of
the straps having buttons and button holes
to permit the garment to be opened at the
neck and slipped on and removed. As
30 shown, the garment also comprises a pair
of short breeches or trunks 4. These parts
may be made of finely-woven fabric and
formed into a one-piece garment or the
breeches may be a separate part and de-
tachably affixed to the waist or body por-
35 tion 2 in any suitable way. Upon this body
ply of fabric 2, I sew another ply or layer
of fabric, thereby making a garment of
double thickness throughout. I may make
the waist portion of double thickness and
40 the yoke and breeches of single thickness,
but assuming the garment to be of two-
ply thickness throughout, I sew the plies
together in such a manner that a number
of air compartments are provided in the
45 waist portion and in sewing them together
I leave certain places open to provide air
communicating passages between the dif-
ferent compartments and an inflating tube
which is formed by an extension 5 at the
50 front of the garment midway of the straps 3.
The outer end of tube 5 has a mouth nipple
6, with or without a valve, whereby the gar-
ment may be inflated within the limits de-
fined by the stitching indicated by the lines
55 7, 10, 12 and 15. Thus, the stitching indi-
cated by line 7 begins at the mouth nipple

and extends down one side of the extension and the front of the yoke and waist portion of the garment to a point relatively near the waist line of the garment, whence it returns on parallel lines to a higher elevation approximately opposite the bottom of the arm opening 8. Thence the stitching extends across the waist toward the arm opening and downwardly on inclined lines underneath the arm opening and continues upwardly at the side of the garment to the back of the garment. A V-shaped area 9 is thus provided underneath the arm hole which is cut off from the air compartment 10 and not capable of being inflated, and the stitching line 7 proceeds across the back of the garment to the other side where a similar V-shaped area 9 is formed underneath the arm hole 8 at that side before the stitching continues across the front of the garment and upwardly to the mouth nipple 6 on lines which are a counterpart of the stitched line made in the first instance. The back of the garment may also be stitched on a median line as indicated at 10, Fig. 3, thereby subdividing the back on a vertical line in substantially the same way as the front part of the garment to produce separate air compartments adjacent each other 85 between the yoke and waist line. The conception involves the production of a series of small pockets in the garment, and in furtherance of this idea, I stitch the outer ply or layer of fabric to the inner layer or 90 ply on parallel lines 12 annularly about the garment excepting over a short space 13 immediately beneath the air tube 5. This space 13 serves as a communicating passage between the upper compartments and an annular passage 14 made at the waist line of the garment by folding or doubling back the outer ply or layer inwardly at its bottom edge and stitching it entirely around the garment to the inner ply of fabric. In 100 this way, the annular compartment 14 is closed completely at its bottom, but nevertheless has open communication with the divisional pockets or compartments at communicating space 13 opposite the inflating tube 5. The openings 15 shown in the outer ply or layer of fabric, one at each side of space 13, are used to introduce a draw string 16 or an elastic band in the narrow space 110 between the parallel stitched lines 12. However, the stitching extends around the openings at each side of space 13 so that the air

is thus cut off from the draw string space and prevented from escaping at the openings 15.

The air space within the garment is localized in definite areas, such as in the belt 11 and in the several pockets formed above the belt at the front and back of the garment, while the yoke and trunk portions of the garment are not inflatable and the space underneath the arm is also cut off from the air to permit freedom of movement of the arms when the garment is worn. The draw string 16 permits the garment to be drawn in and secured closely to the body of the wearer to conform thereto, whereas if no draw string or its equivalent were used the garment would be unduly inflated, and difficult to slip on and off unless an objectionable loose fitting garment was provided. If the breeches are omitted I may also employ a draw string or elastic band within the stitched border 15 at the bottom side of the belt, substantially as indicated in Fig. 4, and the garment may be made of any material suitable for the purpose. The cloth which I actually use is so closely woven that it has the property of being practically air-tight after the garment is soaked in water, and the garment may be immersed in water before it is put on or subsequently.

What I claim is:

1. An inflatable bathing garment comprising a body portion of fabric having an outer lining of fabric stitched thereto on irregular lines forming a plurality of air pockets at the front and back and waist thereof, and provided with an inflating tube formed from and stitched in the layers of fabric, the fabric being closely woven and adapted to be made substantially air-tight when immersed in water.

2. In an inflatable bathing garment, a waist portion made of double ply fabric stitched together on irregular lines above the waist line and on parallel lines annularly at the waist line to provide an annular air belt and a plurality of air pockets.

3. An inflatable bathing garment comprising separate plies of woven fabric stitched together to provide an air belt and a plurality of communicating air pockets between the layers of fabric, said belt and pockets being separated at the waist line of the garment by parallel stitches and a space for a draw or fastening member.

Signed at Cleveland, in the county of Cuyahoga, and State of Ohio, this 24th day of July, 1918.

JOHN REBEL.
